Primary Examiner — Jennifer Rivard*Assistant Examiner* — April Rivas(74) Attorney, Agent, or Firm — Maier & Maier, PLLC(57) CLAIM

The ornamental design for a suitcase, as shown and described.

DESCRIPTION

FIG. 1 is a front left perspective view of a suitcase, showing my new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The solid black portions of the suitcase represent a color contrast.

The broken lines illustrate portions of the suitcase and form no part of the claimed design.
